UNITED STATES PATENT OFFICE.

RALPH H. DOBBS, OF SEATTLE, WASHINGTON

REFRIGERATOR.

No. 883,030.

Specification of Letters Patent.

Patented Oct. 9, 1906.

Application filed July 31, 1905. Serial No. 272,101.

To all whom it may concern:

Be it known that I, RALPH H. DOBBS, a citizen of the United States, residing at Seattle, in the county of King and State of Washington, have invented certain new and useful Improvements in Refrigerators; of which the following is a specification.

My invention relates to certain new and useful improvements in refrigerators; and the primary object thereof is to provide an improved and simplified construction wherein the articles to be preserved will be subjected to a very intense degree of cold.

With the above and other objects in view, to be set forth in the following, the invention consists of the parts, arrangement, and combination of parts hereinafter described, and succinctly pointed out in the appended claims.

In the accompanying drawings, in which like numerals of reference indicate like parts throughout the several views, Figure 1 is a view, partly in front elevation and partly in section, taken on line $y-y$ of Fig. 2, the drawers being removed. Fig. 2 is a section taken on line $z-z$ of Fig. 1. Fig. 3 is a detail fragmentary view in perspective of one of the drawers and the adjacent wall of the refrigerator. Fig. 4 is a detail fragmentary view of one of the walls of one of the inner chambers or compartments adapted to contain the articles to be preserved; and Fig. 5 is a sectional view of a portion of one of the walls of one of the inner chambers or compartments, showing the roller-mountings and a portion of a drawer in elevation.

In carrying out my invention I provide an outer case 1, having a metallic lining 1^a and inner chambers or compartments 2, the latter of which are formed by metallic casings spaced from the top wall of case 1 to provide a main ice-chamber 3 and spaced from each other and the side and rear walls of case 1 to provide vertical ice-chambers 4, 5, and 6. These last-named chambers communicate with the main ice-chamber 3, and therefore ice can be fed thereto from said main chamber and will fall and pack therein by gravity. Chambers 2 terminate or are supported at a point above the bottom of case 1, and therefore ice will fall from chambers 4, 5, and 6 to a point directly beneath the same, said ice moving beneath the lower edges thereof, and, if desired, as will be explained in the following, ice can be placed directly in the lower portions of chambers 2 through openings 7,

formed in the front wall of case 1. Chambers 2, which are open at their fronts, are secured at their sides and rear walls to studing, as 8. It will thus be observed that these chambers are practically surrounded by ice-chambers, and the articles to be preserved will therefore be subjected to intense cold.

The side and end walls of the chambers 2 are formed of sections 9, which are arranged side by side in vertical alinement, and their side edges are formed with bent portions 10, the adjacent portions of the several sections lying in proximity to each other, so as to form air-channels, which are inclined upwardly and inwardly. These channels are indicated by reference-numeral 11, and, as will be observed by reference to Fig. 1, no projecting parts result on the outer faces of these walls to obstruct the ice in its descent, and by inclining the air-channels as specified water is prevented from gaining access to the interior of the chambers.

Within the chambers 2 I mount means for carrying the articles to be preserved, said means preferably being in the form of drawers 12, which are slidabie on rollers 13, secured to the side walls of said chambers. These drawers are spaced apart. Therefore cold air can readily circulate between them, and, further, to insure a more perfect and uniform cooling of the articles contained in the drawers I provide the drawers with foraminous bottoms, as 14.

The front walls of the drawers are extended downward, as at 15, by reason of which construction the front walls of the several drawers will snugly engage one another and entirely close the openings 7 of case 1 and prevent ingress of heat to chambers 2. I also preferably round one side edge of the front wall of each drawer, as at 16, so that the front walls will more readily seat themselves in the opening 7, as is obvious. I provide the chamber 3 with a door 17, so that ice, preferably in crushed form, can be placed therein and fed into the respective chambers 4, 5, and 6, and in addition to supplying the refrigerator with ice from this point the lower drawers 12 can be readily removed and ice also placed directly into the chambers 2 at a point below the positions normally occupied by said drawers. By providing the supporting means for the drawers at the sides of the chambers the interiors of said chambers are left unobstructed and one can

readily reach into the remotest parts thereof when the drawers are removed, or, if the drawers are successively placed in the chambers, starting with the lower drawers, the 5 articles to be preserved can be placed in the drawers subsequent to their insertion in the chambers, thereby obviating necessity of first filling the drawer and then inserting the same into the refrigerator. I preferably provide the drawers with handles, as 18. Any desired type can, however, be employed, and, if desired, holders, as 19, can be attached to the drawers, the same being adapted to receive cards bearing matter indicative of the 15 articles contained therein. A pipe 20 carries off the water of liquefaction from the ice.

In the foregoing I have described a construction which is capable of carrying out the several functions assigned to it. I am aware, 20 however, that the details thereof can be readily varied without departing from the spirit of my invention, and I therefore reserve the right to make such alterations and changes as fall within the scope of the 25 appended claims.

Having thus described my invention, what I claim as new, and desire to secure by Letters Patent of the United States of America, is—

30 1. In a refrigerator, interior walls forming

a chamber, said walls formed of plates arranged in vertical line, the adjacent edges of the plates being bent on one side thereof to form inclined air-passages therebetween.

2. In a refrigerator, interior walls forming 35 a chamber, said walls formed of plates, said plates having flat walls arranged in line, the adjacent edges of the plates being bent on one side of the plate to form upwardly and inwardly inclined air-passages. 40

3. A refrigerator comprising an outer casing, an inner casing forming a refrigerating-chamber, said inner casing being spaced from the side walls of the outer casing forming an ice-chamber and having its bottom open and 45 terminating at a distance above the bottom of the outer casing forming an ice-chamber beneath said inner casing in communication with the first-named ice-chamber, means whereby ice may be supplied to the second-named ice-chamber through the first-named ice-chamber, and means whereby the second-named ice-chamber may be supplied through the refrigerating-chamber. 50

In testimony whereof I affix my signature 55 in presence of two witnesses.

RALPH H. DOBBS.
